AUTOMATIC CARRIAGE RETURN

Harry C. Yaeger, West Hartford, Conn., assignor to Underwood Corporation, New York, N. Y., a corporation of Delaware

Application November 12, 1953, Serial No. 391,640

2 Claims. (Cl. 197—66)

This invention relates to typewriting and similar machines having on a frame an advanceable and returnable carriage, and more particularly relates to control mechanisms for such machines whereby a normally idle power-return mechanism for the carriage is automatically called into operation when the carriage advances to a predetermined position.

The machine of the invention embodies a tabulating mechanism for advancing the carriage rapidly to desired columnar positions. In connection with such tabulating mechanism the machine embodies further means that is effective to suppress or check rebounding of the carriage resultant from the sudden arrest thereof at the end of each tabulating run. Due to the provision of said rebound checking means, a carriage controlling escapement assumes at the end of each tabulating run, immediately and reliably, the appropriate position control over the carriage, and, moreover, the machine is immediately ready for resumption of typing.

As will be evident from the detailed description of the machine which follows, said rebound checking means prevents also movement of the carriage in return direction for a short interval of time after the carriage, in a tabulating run, reaches a certain position defined by a carriage-return-instituting control element. Therefore, it will be appreciated that if a power-return run of the carriage were to get under way while the rebound checking means still blocks the carriage against return movement, then the power return mechanism would become stalled and inoperative.

To the end of providing an efficient machine, incorporating a power carriage return mechanism which is rendered active automatically under carriage control, and incorporating also a carriage tabulating mechanism along with desirable and efficient rebound suppressing means, it is an object of the invention to provide efficient means to enable automatically the power return mechanism under carriage control by a carriage return instituting element but with a sufficient delay so that the power return mechanism will become active only after the stated rebound checking means has done its work and is or has moved from operative position.

Other objects of the invention will become evident in the light of the detailed description of a preferred embodiment of the invention, which follows.

Now having reference to the drawings,

Figure 1 is a right-hand sectional side elevation of a typewriting machine embodying a carriage and a carriage tabulating mechanism.

Figure 2 is a bottom elevation of a typewriter escapement unit along with a tabulation rebound checking mechanism in an idle relation to an escapement wheel, the rear of the machine being towards the top of the view,

Figure 3 is a bottom elevation similar to Figure 2 but the tabulating rebound checking mechanism is shown moved to an active position,

Figure 4 is a bottom elevation as Figures 2 and 3 are, showing the rebound suppressing mechanism about to become inactive,

Figure 5 is a perspective illustration of a carriage re-

2

turn control mechanism in normal position, the direction of vision being forwardly and downwardly from the rear of the machine, toward the right,

Figure 6 is a left-hand side elevation of certain parts of the carriage return control mechanism seen in Figure 5, in their normal positions,

Figure 7 is a view similar to Figure 6 but certain of the parts are shown operated,

Finally, Figure 8 is a fractional rear elevation, showing a carriage return clutch in open position, along with a related controlling mechanism.

Referring now more particularly to Figure 1 of the drawings, a typewriter framework 10 comprises opposite side walls 11 and a trackway 12. A carriage 13, by means of a carriage rail 14, is guided upon said trackway 12 for opposite travel in advance and return directions. Said carriage 13 includes ends 15 carrying a platen roll 16 which is adapted to support work sheets for reception of typing impressions, all in a usual manner. Above and to the rear of the rail 14 the carriage 13 supports a rack bar 24 having thereon at letter space intervals usual key-settable tabulating stops 17.

A frame-supported spring motor 18 has an operative connection with the carriage 13, in a usual manner, for urging it impositively to advance leftwardly, that is, in letter feed direction. However, in a conventional manner, movement of the carriage in the letter feed direction is controlled by an escapement generally designated by the numeral 19, in cooperation with an escapement wheel 20. The latter rotates synchronously with the movement of the carriage, a rack 23 on the carriage rotating a gear 22 and the latter being connected with the escapement wheel 20 through a shaft 21.

Normally the carriage is held at rest against the urge of the spring motor 18 in that one of the teeth on the escapement wheel 20, see Figure 2, abuts against the end of a holding dog 27. The dog 27 is carried pivotally on the underside of a rocker element 30 of the escapement 19, and said element 30 is rockably mounted on trunnions 31. On the top side the rocker 30 carries a usual stepping dog 32 which normally is clear above the teeth of the escapement wheel 20, and held advanced in respect to the holding dog 27 by means of a spring 33. The spring 33 also serves to bias the holding dog 27 into the orbit of the wheel teeth.

Incidental to each typing operation the escapement rocker 30 is vibrated in a usual manner, first to swing the dog 27 downwardly clear of the active wheel tooth, thereby to free the carriage to take a letter feed step under power of the spring motor 18. This swings the stepping dog 32 into intercepting position of the next wheel tooth, and after the escapement rocker 30 has vibrated oppositely, the holding dog 27 will be in control of the next tooth 28. During carriage returns the escapement wheel 20 rotates in a direction opposite to the arrow indicated in Figure 2 and the teeth of the escapement wheel 20 crowd the escapement dog 27 idly outwardly.

The illustrated machine is shown to embody the power-actuated tabulating mechanism of the patent to Helmond, No. 2,303,878, dated December 1, 1942. Said tabulating mechanism comprises a counterstop reed 37 which is projectable upwardly from the position seen in Figure 1, into the range of any set tabulator stop 17. At operation of a tabulator key 38, a transversely extending lever 39 swings downwardly to depress a lever 40 having a hook element 50 to draw a power actuator 51. This engages a snatch pawl 53 with a constantly turning, toothed, power member 52. Said actuator 51 is borne pivotally on a pendant arm 54 and a spring 55 urges the same rearwardly, and upwardly away from the toothed power member 52, normally to occupy the idle position seen in Figure 1. The actuator receives a forward power

movement whenever the snatch pawl is brought into engagement with the toothed shaft 52. There ensues then an operation of a link 56 which rocks a structure 57 including a shaft 59 about an axis defined by the latter. This structure 57, by means of a link 58 and a lever 60 imparts an upward movement to the reed 37. The upper end of the reed 37 reaches through a perforation provided in a top plate 63 of a tabulator housing 64 and spring means 67 biases the reed downwardly and rightwardly. Said perforation is wide enough to allow some lateral movement of said reed 37 and so that at projection of the reed a latch edge 65 thereon will catch rightwardly over a plate 66. Whenever the reed 37 is projected, the lever 60 operates a bell crank 68 carried pivotally at 70. During the first part of the projecting movement of the reed 37 a downreaching arm 71 of the bell crank 68 moves first idly from the position seen in Figure 2. After the upper end of the reed 37 has moved above the lower edge of an active tabulator stop 17, said arm 71 will pick up and swing the holding dog 27 clear of the escapement wheel tooth which has to this moment been active. The carriage resultingly takes a tabulating run in letter feed direction until a tabulator stop 17 engages and displaces the projected reed 37 leftwardly to the limit in the perforation. This places the latch edge 65 free of the plate 66 so that the spring 61 associated with the reed will retract the latter to normal position. During such retraction of the reed, the downreaching arm 71 of the lever 68 swings rearwardly and renders the holding dog 27 free for movement to effective position under the power of the spring 33, see Figure 2. The movement of the arm 71 in regard to controlling the dog 27 is such that the latter will move to holding position before the tabulator reed 37 moves fully below the tabulator stop 17.

The sudden violent arrest of the carriage at the encounter of the tabulator stop 17 with the reed 37, especially after long tabulating runs, results in violent rebounding action of the carriage, and the machine includes means which at the end of each tabulating run is effective to check rebounding of the carriage, thereby to assure the eventual settling of the carriage in the proper letter feed position.

The particular rebound checking means shown in that of the patent to Yeager, No. 2,647,611, issued August 4, 1953, and includes a reverse rotation checking pawl 76 for the escapement wheel 20, pivotally carried at 77 on the underside of the escapement bracket 25. The pawl 76 occupies normally a position fully clear of the orbit of the teeth of the escapement wheel, see Figure 2. At each institution of a tabulating run the downreaching arm 71 of the bell crank 68, through the intermediary of a connection comprising an interponent rod 78, imparts a forward swinging motion to a lever 80 reaching in Figures 2 and 3 leftwardly from a pivot point 81 on the bracket 25. Toward the end of the forward swinging motion of the lever 80 a pin 82 engages a rear face on a lever 84 to swing the latter to the position seen in Figure 3. The lever 84 is pivotally carried by a stud 85 on the bracket 25 and is yieldingly connected with the reverse-rotation check pawl 76 by a spring 87. Therefore, when the lever 84 is in the operated position seen in Figure 3, the spring 87 urges the pawl 76 into reverse-rotation checking relation with the escapement wheel 20. During the movement of the levers 80 and 84 to their operated positions seen in Figure 3, a latch element 88 pivotally carried at 90 on the lever 80, facilitated by a spring 91, glides over an ear 92 on the lever 84 to arrive finally in the position seen in Figure 3. During tabulating movement of the carriage, and while the tabulator reed 37 remains projected, the lever 80 remains operated and therefore the check pawl 76 is posed for action. During the tabulation the escapement wheel 20 turns in the direction of the arrow indicated in Figure 3,

the escapement wheel teeth ratcheting past the check pawl 76 idly. As the tabulator stop 17 meets the counterstop 37, one of the escapement wheel teeth will have passed slightly beyond the check pawl 76 and the latter will spring-move into rebound checking position behind such tooth. When the tabulator stop 17 encounters the counterstop reed 37, it will displace it leftwardly free of the plate 66 for restoring action under the power of the spring 61. Before the reed 37 restores, the active tabulator stop will have displaced the reed 37 leftwardly to the full limit and the carriage 13 rebounds. The rebound check pawl 76 meanwhile stands ready in position to stop reverse rotation of the escapement wheel 20, as shown in Figure 3, said check pawl 76 being backed up by a motion limiting pin 96. During an initial portion of the restoring movement of the counterstop reed 37, before the same moves below the tabulator stop 17, the escapement wheel dog 27 moves to the escapement wheel controlling position seen in Figure 2. Meanwhile, the back check pawl 76 is held active by the latch 88 in cooperation with the ear 92.

After the parts assume the position seen in Figure 4 the reed concludes its retracting movement and the lever arm 71 assumes the normal position of Figure 2. During the very last increment of retracting movement of the reed 37 the pawl 88 rides off the edge of the ear 92, wherefore the reverse-rotation check pawl 76 stays active sufficiently late beyond the instant of rebounding action of the carriage. The spring 91 therefore returns the lever 84 to the normal position seen in Figure 2, an arm 86 forcing the pawl 76 to idle position. Meanwhile the carriage 11, under the power of the spring motor 18, settles in the exact desired letter feed position.

Additionally to the rod 78, the connection between the arm 71 and the lever 80 comprises extending therebetween a spring 97 having the said rod 78 accommodated in the turns thereof. The spring 97 is very strong and always confines rod 78 snugly between the arm 71 and an adjustable screw 100 on the lever 80. The effect is that the rod 78, the spring 97 and the screw 100 constitute together an adjustable connection between the arm 71 and the lever 80, it being understood that the screw 100 is so adjusted that the latch 88 will move clear of the ear 92 at the last possible moment of the restoring movement of the arm 71, thereby to keep the check pawl 76 sufficiently long capacitated to perform its intended function.

The machine of the invention further embodies a power return mechanism for the carriage. Such mechanism may be generally of the design disclosed in the patent to Helmond, No. 2,262,676, dated November 11, 1941, but is not limited thereto.

Referring now to the rear elevation of Figure 8 there is shown a carriage return clutch element 102 which, while the machine is in use, is constantly driven by the motor 103 shown in Figure 1 through the medium of a speed reduction drive, not shown. Axially in line with said clutch element 102 and normally separated therefrom is another clutch element 104 having an annular groove 105. The said clutch element 102 is carried fast upon a motor-driven shaft 106 whereas the clutch element 104 is turnable independently of such shaft. Concentrically arranged on the shaft 106, also turnable independently thereof, is a pulley 108 from which a carriage return drawband 110 passes upwardly over a guide sheave 111 and thence to the left carriage end whereat it is connected to a line spacing mechanism, not shown. The pulley 108, under the tension of a weak clock spring, not shown, keeps the drawband 110 lightly wound thereupon. The parts just described are located at the rear of the machine near the right side wall 11.

The clutch member 104 has a spline connection with the pulley 108, as indicated at 109, and normally, as stated hereinbefore, is separated from the clutch member 102

and thus normally is not motor driven. A clutch controlling fork 112, carried on a shaft 113, is associated with the clutch member 104 in the groove 105 thereof to shift it between an open and a closed clutch position. Said fork 112 is operable to the closed clutch position by a lever 114 that is pivoted at 115, and has a link connection 116 with an arm 117 fast upon the shaft 113. A spring 118 constantly tends to have a clutch closing influence on the fork 112. Normally, however, see Figure 5, the described mechanism is held against the power of the spring 118 in open-clutch position by a latch 120 that is pivotally carried at 121 upon the outside of the right side wall 11 of the machine. The said latch 120 is biased to the effective position by a spring 122 and is releasable in a conventional manner under control of a carriage return key, not shown. Said latch 120 is also releasable under carriage control, automatically, by mechanism to be described presently. The carriage 13 upon a rack 123 carries a carriage return instituting element or stop 124, as well as a carriage return terminating stop 124a, see Figure 5, said stops being adjustable along said rack, respectively to different return instituting and return terminating positions. As the carriage letter-steps or tabulates to the return instituting position defined by the stop 124, the latter engages and displaces a short distance in letter feed direction a counterstop element 125 on the machine frame. Such counterstop element may be in the form of an upright arm arranged at the rear of the machine pivotally upstanding and rockable about a stud 126 between limits afforded by a perforation 127 provided in the top plate 63 of the tabulator housing. Normally, when viewed from the front of the machine, the said counterstop arm 125 bears under the tension of the spring 128 against the right limit afforded by said perforation 127. When said return instituting element 124 displaces the counterstop arm 125 leftwardly (rightwardly in Figure 5), then a pin 130 on the latter operates a bell crank 131 which also is pivotally rockable on the stud 126. Upon a rightwardly extending portion of said bell crank 131 there is carried pivotally at 133 an adjunct arm 134. An ear 135 on the arm 134 normally abuts the underside of the adjacent portion of the bell crank 131. This is under the urge of a spring 136 extending between the ear 135 and another ear on the bell crank 131. Articulated to said arm 134 in an upreaching relation is a releaser 137 for the latch 120, having an offset nose 138 underlying normally idly an ear 140 on the latch 120, the nose being communicative through a hole in the wall 11. At the upper end said releaser embodies a fork 141 straddling a guide pin 143 projecting inwardly from the right side wall 11 of the machine.

In the movement of the carriage to the return instituting position, the carriage-carried element or stop 124 displaces the counterstop element 125 leftwardly as seen from the front of the machine. It will be evident later herein that if such movement is effected independently of the tabulating mechanism, such as by letter-feed motion of the carriage, arm 134 will become operated immediately with the bell crank 131 and will move the releaser 137 promptly upward, the nose 138 swinging the latch 120 clear of the clutch closing lever 114, it being understood that the spring 136 is stronger than the latch restoring spring 122. At release of said latch 120, the lever 114 snaps upwardly to clutch closing position under the tension of the spring 118. The fork 112 in such movement engages the clutch element 104 with the companion clutch element 102. Consequently there ensues a power return run of the carriage. The lever 114, under the tension of the spring 118 stays in closed clutch position while the carriage returns, and, moreover, a stud 143 on a member 144 that extends leftwardly from an upreaching arm of the lever 114 will then have moved leftwardly to keep the counterstop arm or element 125 against the left edge of the perforation 127.

Ultimately in the power return run of the carriage the return terminating stop 124a engages and moves forcibly the counterstop arm or element 125 rightwardly as seen from the front. The stud 143 is thus also moved rightwardly and this results in the restoration of the lever 114 to the control of the latch 120, thereby rendering the carriage return clutch open and terminating the return run of the carriage.

A return run of the carriage may also be instituted as 10 a result of a tabulating movement of the carriage to the return instituting position defined by the carriage carried element 124. At the end of a tabulating movement to such position, neither the tabulator reed, nor the before-described rebound checking element 76 must obstruct the return run of the carriage. Accordingly, provision is made so that as the carriage in its tabulating movement reaches return instituting position and the counterstop element 125 is moved leftwardly, an arm 145 carried fast on such counterstop element 125 moves also 15 the tabulator reed 37 leftwardly. This frees the reed ledge 65 from the shelf 66 and the reed 37 restores downwardly under the urge of the spring 61. The carriage is then free to return insofar as the tabulator reed 37 is concerned, but its return must yet be delayed to give 20 the carriage rebound check pawl 76 time to move clear of the escapement wheel before the carriage return drive becomes active. According to the invention, provision is made so that in connection with a carriage return institution resultant from a tabulation, the control over the 25 power return clutch 102, 104 is such that the return run of the carriage will start only after the check pawl 76 has moved to idle position following the tabulating movement. Specifically, there is provided near the right side wall of the machine, fast on the shaft 59 of the tabulating 30 control mechanism, an upreaching arm 146. When the tabulating mechanism is in normal position, as in Figure 1, then said arm 146 is in the position seen in Figure 6. In such position of the arm 146 a spring 151 holds a slide element 147 so that an ear 148 thereof lies 35 rearwardly of the longer prong 149 of the fork 141. The said prong 149 is thus normally free for upward, carriage-return instituting movement and this condition prevails also whenever the carriage is moved to the return 40 instituting position without use of the tabulating mechanism. Therefore, whenever the carriage is advanced independently of the tabulating mechanism to the position in which the element 124 operates the counterstop 125, then the operation of the return instituting latch 120 is 45 instantaneous. On the other hand, whenever the tabulator key 38 is operated the power actuator 51 rotates the shaft 59 so that the arm 146 moves from the position seen in Figure 6 to the position seen in Figure 7. Initially in such movement the spring 151 draws the slide 147 forwardly until it is intercepted by a pin 153 on 50 the frame. This places the ear 148 into a blocking position over the latch releaser prong 149. The arm 146 has a pin-and-slot connection 150 with the slide 147 and the spring 151 is provided intermediate the slide 147 and the arm 146 to allow the latter to complete its movement after the slide 147 is intercepted by the pin 153, as seen in Figure 7. The ear 148 reaches the position seen in Figure 7 immediately in the stated movement of the arm 146 and during the remainder of the movement the spring 151 yields.

The arm 146 remains operated in each tabulating operation until the tabulator reed 37, upon being freed for downward movement, either by the tabulator stop 17 or the leftward operation of the arm 145, arrives in fully restored position. Thus, only in the very last part movement of the arm 146 from the Figure 7 to the Figure 6 position does the ear 148 free the releaser prong 149 for upward movement. If the carriage moves toward return instituting position consequential to a tabulating operation then the carriage supported return instituting element 124 will encounter and operate the counterstop

125, operating the bell crank 131. Inasmuch as in tabulations the releaser 137 stands blocked by the ear 148, the movement of the bell crank 131 will not be transmitted to the arm 134 but will cause the flexing of the spring 136, placing the arm 134 under a strong upward bias. The releaser remains blocked by the ear 148 until the tabulating mechanism, including the reed 37, approaches fully restored position, at which time the arm 146 forces the slide 147 rearwardly to the Figure 6 position, and thereby forces the ear 148 off the prong 149. This frees the releaser 137 for upward movement under the bias of the spring 136 which has remained flexed by the bell crank 131. The rebound checking pawl 76 which during the tabulation has been potentially held active by the pawl 88 restores to normal position at about the same instant. A little before, the arm 71 of the tabulating mechanism places the escapement dog 27 into cooperative relation with the escapement wheel.

It will thus be perceived that although the return instituting element 124 is allowed to operate the element 125, the releaser 137 functions to release the latch 120 only when the tabulating mechanism assumes completely restored position and the rebound checking mechanism is incapacitated. Upon release of the latch 120 the clutch fork 112 closes the return clutch under the power of the spring 118. The carriage then commences to be power-retumed after the drawband 110 has operated the line spacer.

The provision of the spring 136 intermediate the bell crank 131 and the arm 134 allows the carriage to tabulate fully to the return instituting position. Therefore, the arm 145 on the return instituting counterstop element 125 at the end of a tabulation to line-end position will always displace the tabulator reed 37 to cause its restoration, as well as the restoration of the entire tabulating mechanism including the blocking element 147. If the yield provided by the spring 136 were not provided, then the counterstop element 125 would be incapable of operation during a tabulation and in turn the arm 145 on the return instituting element 125 would be incapable of causing the restoration of the tabulating mechanism. The blocking element 147 would therefore remain in effective position and no automatic return could ensue.

The operation of the return instituting element 125 occurs in a movement of the carriage equivalent to a letter feed step thereof and results in an operation of an arm 155 indicated in Figure 5 to operate a type key locking mechanism, not shown.

All carriage return runs called into operation independently of a tabulating operation, including such called into operation by a return key, not shown, occur without delay. Carriage return operations ensuing on the other hand due to tabulating movement of the carriage to return instituting position are instituted with a delay sufficient to give the described rebound checking pawl 76 time to withdraw and free the carriage for power return movement.

Having explained the nature and the objects of the invention, and having specifically described a machine embodying the invention in its preferred form, what is claimed is:

1. The combination with a typewriting machine having a carriage movable on a frame in advance and in return directions, of a power return drive adapted to be closed and opened, means movable from a normal to an operated position and reversely, respectively to close and open said power return drive, spring means biasing said movable means to close said power return drive, a latch mechanism normally holding said movable means in normal position, a carriage-carried carriage return instituting element, an element carried on the frame for operation by said carriage return instituting element at advance movement of the carriage to a certain position, tabulating mechanism for the carriage comprising a tabulator stop, a counterstop key-projectable into tabulation-terminating

range with said tabulator stop, and means responsive to the encounter of said tabulator stop with said counterstop to retract said counterstop automatically, a normally idle device responsive to the retraction of said counterstop to check rebounding of the carriage momentarily and incidentally thereto obstructing momentarily movement of the carriage in return direction, means responsive to the operation of said frame-carried element by said carriage-carried carriage return instituting element, to retract said tabulator counterstop if it has been projected, means conditionable for resilient releasing action on said latch mechanism by the operation of said frame-carried element, and a member moved into a release-blocking relation with said conditionable means by the projection of the tabulator counterstop, and moved out of such blocking relation by the retraction of such counterstop, said conditionable means and said member having shoulders movable transversely to each other which are correlated so that the shoulder on said member moves into blocking relation with the other shoulder initially as said counterstop is being projected and conversely moves clear of such other shoulder only when said counterstop reaches substantially fully retracted position, whereby if said frame-carried element is operated as a result of a tabulation, the release of said latch mechanism ensues only as said tabulator counterstop becomes fully retracted, giving time for said rebound checking device to function and withdraw before the carriage begins its power return.

2. The combination with a typewriting machine having a carriage movable on a frame in advance and in return directions, of a power return drive adapted to be closed and opened, means movable from a normal to an operated position and reversely, respectively to close and open said power return drive, spring means biasing said movable means to close said power return drive, a latch mechanism normally holding said movable means in normal position, a carriage-carried carriage return instituting element, an element carried on the frame for operation by said carriage return instituting element at advance movement of the carriage to a certain position, tabulating mechanism for the carriage comprising a tabulator stop, a counterstop key-projectable into tabulation-terminating range with said tabulator stop, and means responsive to the encounter of said tabulator stop with said counterstop to retract said counterstop automatically, a normally idle device responsive to the retraction of said counterstop to check rebounding of the carriage momentarily and incidentally thereto obstructing momentarily movement of the carriage in return direction, means responsive to the operation of said frame-carried element by said carriage-carried carriage return instituting element, to retract said tabulator counterstop if it has been projected, means conditionable for resilient releasing action on said latch mechanism by the operation of said frame-carried element, and a slide moved into release-blocking relation with a part of said conditionable means by the projection of the tabulator counterstop and moved out of such blocking relation by the retraction of such counterstop, said slide having a shoulder movable transversely to the operating path of said part, initially as said counterstop is being projected, and said shoulder being moved clear of said part only when said counterstop reaches substantially fully retracted position, whereby if said frame-carried element is operated as a result of a tabulation, the release of said latch mechanism ensues only as said tabulator counterstop becomes fully retracted, giving time for said rebound checking device to function and withdraw before the carriage begins its power-return.
